UNITED STATES PATENT OFFICE.

PETER J. SEFERLIS, OF ITHACA, NEW YORK.

KEY-RING HOLDER.

1,418,979.

Specification of Letters Patent. Patented June 6, 1922.

Application filed March 29, 1922. Serial No. 547,756.

To all whom it may concern:

Be it known that I, PETER J. SEFERLIS, a citizen of the United States, residing at Ithaca, in the county of Tompkins and State 5 of New York, have invented certain new and useful Improvements in Key-Ring Holders, of which the following is a specification.

This invention relates to certain new and useful improvements in key ring holders and 10 has particular reference to that type of holder embodying a clasp adapted for attachment to apparel, such as the waist band of trousers, with the key ring carried by the clasp.

15 The primary object of the invention resides in the provision of a key ring holder in the form of a clasp having an arm received over the waist band of trousers or other parts of the wearing apparel and further embodying a looped portion for 20 supporting a key ring to prevent accidental displacement of the key ring from the clasp.

A further object of the invention resides 25 in a key ring holder of the type above set forth, the provision of a spring finger carried by the body of the clasp normally engaging the looped end of the clasp to receive the key ring to prevent accidental displacement of the key ring from the clasp, 30 the looped end of the clasp being compressible to displace the spring finger from the terminal engagement therewith to permit easy removal of the ring from the clasp.

With the above general objects in view the 35 invention consists of the novel combination and arrangement of parts hereinafter more fully described in connection with accompanying drawings, and in which like reference characters designate corresponding 40 parts throughout the several views.

In the drawings:—

Figure 1 is a perspective view of a key ring holder constructed in accordance with the present invention, showing the same as 45 attached to a garment as indicated by dotted lines,

Figure 2 is a side elevational view of the key ring holder supported on a garment with a key ring mounted therein, showing the 50 terminal end of the spring finger engaging the key supporting arm to prevent displacement of the key ring from the arm,

Figure 3 is a side elevational view, similar to Figure 2 showing the key ring supporting 55 arm moved inwardly to displace the terminal end of the spring finger therefrom to

permit removal of the key ring, as indicated by dotted lines, and

Figure 4 is a developed plan view of the key ring holder.

Referring more in detail to the accompanying drawings, there is illustrated a key ring holder formed of a resilient strip of material having a central body portion 1 to be bent upon the line 2 as shown in Figure 65 4 provides a garment engaging clasp section 3 having the outer end 4 thereof bent to provide a substantial hook for engagement with the garment G as shown in Figures 1 to 3.

The opposite end of the central body portion 1 is bent upon the line 5 to form a key ring supporting loop 6 and an outer tapering guard arm 7.

The gist of the invention resides in the provision of a spring finger 8 struck out 75 from the resilient body portion 1 as shown in Figure 4 with the terminal end 8^a as shown in Figure 2 normally engaging the adjacent face of the guard arm 7 providing a closed loop portion between the body 1 80 and the guard arm 7 to prevent the accidental displacement of the key ring R as shown in Figure 2.

When placing the key ring R upon the holder, the ring is moved into the space between the end of the guard arm 7 and the adjacent portion of the spring finger 8, the end being forced between the arm and finger against the resiliency thereof to assume the position shown in Figure 2, at which time 90 the ring R is locked in the holder. When it is desired to remove the ring from the holder, the ring may be grasped between the fingers and palm of the hand and the thumb shown by dotted lines in Figure 3 pushed 95 inwardly upon the outer end of the arm 7 to displace the inner end 8^a of the spring finger 8 from engagement with the guard arm as shown in Figure 3, at which time the ring R is moved between the inner end 8^a of 100 the finger and the guard arm to be subsequently freely removed from the holder.

The spring finger 8 will absolutely prevent accidental disengagement of the ring R from the holder, it being necessary that the outer 105 end of the guard arm 7 be pressed inwardly for removing the inner end 8^a of the spring finger from engagement with the guard arm.

While there is herein shown and described the preferred embodiment of the invention, 110 it is to be understood that minor changes in the construction, combination and arrange-

ment of parts may be made without departing from the spirit and scope of the invention.

Having thus described the invention, what I claim as new is:—

1. A key ring holder comprising a resilient strip of metal bent to provide a garment engaging clasp, a body portion and a guard arm, a spring finger struck out from 10 the body portion having the terminal end thereof engaging the guard arm to form a closed loop for the key ring, said ring being removable from the holder by pressure upon the outer end of the guard arm to disengage 15 the terminal end of the spring finger from engagement with the guard arm.
2. In a key ring holder of the type described, a strip of resilient metal bent to

provide an intermediate body portion, a garment attaching clasp, and a guard arm, a 20 spring finger struck out from the central body portion with the outwardly projecting terminal end thereof contacting the inner 25 face of the guard arm at a point spaced from the end thereof and to provide a closed loop portion between the central body and the guard arm, a key ring supported within said looped portion being removable from the holder by pressure upon the outer end of the guard arm to displace the terminal end 30 of the spring finger from engagement with the guard arm to provide a receiving space between the finger and arm for the reception and passage of a key ring.

In testimony whereof I affix my signature. 35

PETER J. SEFERLIS.
